UNITED STATES PATENT OFFICE.

ARTHUR M. LESLIE, OF CHICAGO, ILLINOIS.

ROTARY-SHUTTLE SEWING-MACHINE.

SPECIFICATION forming part of Letters Patent No. 241,553, dated May 17, 1881.

Application filed January 28, 1880.

To all whom it may concern:

Be it known that I, ARTHUR M. LESLIE, of Chicago, Illinois, have invented a new and useful Rotary-Shuttle Sewing-Machine, of which the following is a specification.

5 This invention relates to improvements in lock-stitch sewing-machines of the rotary-shuttle type.

The general object of the invention is to embody the rotary-shuttle principle in a sewing-machine possessing the standard qualities of noiselessness, light running, and perfection of stitch in a superior degree, with convenience of manipulation, uniformity of action, and simplicity of construction.

10 Said invention consists more particularly, first, in means for releasing and throwing out the bobbin of a rotary shuttle without disturbing the shuttle or its race; secondly, in means for releasing the bobbin of a rotary shuttle by the pressure of the finger; thirdly, in means for thus releasing said bobbin and at the same time ejecting it, without subjecting the bobbin to constant pressure; and, fourthly, 15 in improved means to prevent twisting the thread of a rotary shuttle and for giving the same the requisite tension and regulating the latter independently of the bobbin and bobbin-retaining devices.

20 Said invention consists, fifthly, in means to facilitate the release of the needle-loops by a rotary shuttle driven at high speeds; and, sixthly, in means for adjusting a rotary shuttle-driver so that the shuttle can be readily 25 timed or its time varied.

It consists, seventhly, in a peculiar combination of parts in a rotary-shuttle sewing-machine, including rotary shafts in the arm and beneath the cloth-plate and mechanism connecting said shafts, the under shaft turning alternately fast and slow for driving the shuttle at high speeds with superior economy of power and for releasing the needle-loops by periodically opening a space between the heel 40 of the shuttle and its driver.

45 It consists, eighthly, in the addition to said combination of a central bobbin, the parts being so timed that the bobbin is carried through the needle-loops at the greatest speed of said 50 under shaft, the needle-loops being thus formed and released quickly enough without multiply-

ing the motion of the under shaft, notwithstanding the relatively-large size of loop demanded by a central bobbin.

Said invention consists, ninthly, in the addition to the combination last named of an independent positive motion take-up and means for actuating the same, these parts serving to let down ample thread for the needle-loops during the fast motion of the under shaft and 55 to take up the slack after the loops are released by the shuttle.

It consists, tenthly, in a peculiar combination and arrangement of parts, whereby the take-up lever is adapted to draw the upper 60 thread from the needle in a nearly-direct line, and said thread is relieved from unnecessary friction and strain between the upper tension device and the needle.

It consists, eleventhly, in means to facilitate 65 assembling said rotary shaft mechanism.

Said invention consists, twelfthly, in a peculiar combination and arrangement of parts, whereby certain feed mechanism is located in compact form immediately at and behind the 75 feed-dog on the bottom of the cloth-plate and regulated from the customary point in front of the standard; and, lastly, in simple and effective means for adjusting the feed-dog vertically, to regulate the projection of its teeth, 80 as hereinafter more fully set forth.

Figure 1 of the accompanying drawings is an end elevation of my said rotary-shuttle sewing-machine, and Fig. 2 is a horizontal section through the rotary shuttle and its race and 85 driver on the line 2/2, Fig. 1. Fig. 3 is an elevation of the machine-head from the back thereof, showing more particularly the take-up, with the guides and tension for the upper thread, the head being shown as if broken from the arm, 90 with the upper shaft in cross-section. Fig. 1^a is an end view of the under shaft, showing the shuttle-driver disk. Fig. 1^b is a like view, showing the shuttle-driver with the latter partly in section; and Fig. 2^a is an edge view of the 95 shuttle-driver and its disk. Fig. 1^c is a perspective view of the bobbin-case and bobbin separated, and Fig. 2^c is an axial section of the bobbin-case with the bobbin in it. Fig. 1^d is a face view of the shuttle with the bobbin-case and bobbin removed. Fig. 2^d is a section of the same on the line correspondingly num- 100

bered, and Fig. 3^a is a back view thereof. Fig. 2^b is a top view of the presser-foot detached. Fig. 4 is a vertical longitudinal section of the machine, and Fig. 5 is a vertical section through the standard of the same on the line 5 5, Fig. 4, showing more particularly the combination of rotary shafts. Fig. 6 is a bottom view of the machine, partially in section; and Fig. 7 is a partial vertical section on the line 7 7, Fig. 6, showing more particularly the feed mechanism. The figures numbered 1 to 3, inclusive, and Figs. 1^a, 1^b, 2^a, 2^b, Sheets 1 and 2, are drawn to one scale; Figs. 1^c, 2^c, 1^d, 2^d, and 3^a to a larger scale, and the other figures, Sheets 3 and 4, to another and smaller scale.

Like letters of reference indicate corresponding parts in the several figures.

A hollow rigid arm, A, unites the cloth-plate C and head H of this machine, and these three parts support the operative mechanism.

A reciprocating needle-bar, B, works vertically in guides formed within the head H, and carries at its lower end a short straight needle, N, to which an upper thread, 1, is fed from a commercial spool, s.

Immediately in front of the plane of the needle a segmental rotary shuttle, S, works in a vertical transverse plane within a shuttle-race, R, which is formed by a braced and recessed projection cast on the bottom of the cloth-plate, together with a segmental annular cap, c, attached to the planed face of said projection by screws. The shuttle S has a concentric annular bobbin-chamber, e², in its outer face, with a recessed hub, h, at the center of said chamber, and a recess extending radially from that of said hub and terminating in a slot outside of said chamber, and an annular disk-bobbin, b, with an annular bobbin-case, b², are arranged in said chamber, and a finger-lever, l, and latch l² are placed within said slot and recesses. Said lever l works on a pivot parallel to the face of the shuttle, as shown in Figs. 1^d and 2^d, and operates the latch l² by means of a shoulder, k, Fig. 3^a, which engages the extremity of one leg of said latch, the latter being of L form, with one leg dovetailed and adapted to slide in said radial recess and to engage with said shoulder of the lever, and the other adapted to work within said recess of the hub and to engage with the face of the bobbin-case b², at the outer extremity of said hub, as illustrated by Figs. 1, 1^d, and 2^d. The latch, through said lever as a part thereof, is thus exposed at the face of the shuttle within the opening of said race-cap e so as to be easily reached, and is retracted by the simple pressure of the finger on said lever. The bobbin-case and bobbin are thus very readily released at will. A projecting spring, j, is supported behind the outer leg of the latch l², within the hub h, by a little screw introduced longitudinally of the latter, as shown in Fig. 2^d. When released the bobbin and bobbin-case are thrown out or protruded by an ejector, e, so as to be readily taken from the shuttle through

said opening of the race-cap. This ejector is combined with the lever l in the form of a spring-finger projecting from the heel of said lever into said radial recess behind the bobbin-chamber e², being accommodated by cutting away one side of said sliding leg of the latch l², as shown in Figs. 1^d and 3^a.

The bobbin-case b², Fig. 1^c, has a central sleeve, s², fitted to the shuttle-hub h, and the bobbin b rotates upon said sleeve free from contact with any part of the shuttle. When the bobbin and bobbin-case are in place, as shown in Figs. 1 and 2, the latter is rendered non-rotary by the under thread, 2, which is always taut between the upper edge of said bobbin-case and the cloth, owing to the location of a tension-spring, t², on the face of said case at said edge, from which the under thread, 2, is drawn by the feed as required. The under thread is carried from the bobbin b first radially, through a notch, h², Fig. 1^c, in the case b²; thence horizontally out of the bobbin-chamber, within a groove, g, in the periphery of said case; thence through a notch, h³, in said tension-spring t², and preferably once around said spring, and thence to the cloth. The pressure of the spring t² is regulated by a little screw, r, working in a tapped support, s³, which is attached outside of the spring. The under tension may, consequently, be readily regulated without unthreading it, while the threading operation, when a full bobbin is inserted, is rendered very simple. The tension is, moreover, wholly upon the thread, and consequently the same, whether the bobbin be full or empty.

To reduce the unequal effect of centrifugal force upon the segmental shuttle S, its thicker side is cut away or slotted, as shown at z, and this, I have discovered, can be carried to the extent indicated without destroying the desirable tendency of the shuttle to separate from its driver D by centrifugal force, so that the needle-loops may pass between. Heretofore the tendency of the rotary shuttle to fly outward has been so great at high speeds as to seriously increase the friction of the shuttle within the race, and thus to occasion excessive pressure of the driver D against the heel y of the shuttle. To further utilize the remaining outward tendency of the shuttle S, its circumferential flange f is rounded; or it may be beveled on its outer face, its back being flat, and the guide-groove g², formed by the cap c, is made to correspond, so that said outward tendency shall press the point x of the shuttle upward and toward the needle. I thus insure catching the needle-loops after the parts are worn and when running at the highest speed. The shuttle is located as high as is practicable for economy of motion, and the shuttle-race and its cap are made open at top to admit the needle and to provide for the passage of the threads, and all the parts of this mechanism are made snug and smooth, so as not to catch or cut either thread.

The shuttle S is rotated by means of a driver, D, the effective portion of which is a segment-

al projection behind the heel y of the shuttle within its race, as shown in Fig. 1, this driver being carried by a circular disk, D^2 , which closes the back of the shuttle-race, and is, in turn, carried by a horizontal rotary shaft, S^2 . The driver D extends inward across the end of said shaft, having at its inner extremity a pin, p , which is fitted to an axial socket, a , in the shaft. (See Figs. 1^a, 1^b, 2^a.) A screw, s^4 , 10 passes through the body of the driver into one of a series of tapped holes, h^4 , in the driver-disk D^2 , the series rendering the driver adjustable at will relatively to the feed-cam c' , which is, by preference, cast with said disk, as 15 shown. The driver is slotted or bifurcated, as shown in Figs 1^b, 2^a, to permit the needle to descend in advance of the passage of the driver and to protect the needle-loop, x^2 being the heel of the driver, which is followed by the 20 point x of the shuttle.

The needle-bar B is driven by a crank-disk, D' , on a rotary shaft, S' , said disk having a friction-roller wrist, which works in a grooved cross-head, H' , with which said bar is provided within the head H , as shown in Figs. 3 and 4. Said shaft S' extends horizontally through the horizontal portion of the arm A , being supported by bearings at the respective extremities thereof. One end carries the needle-driver, as aforesaid. The other end protrudes and is furnished with a double pulley, P , of two diameters, and a hand-wheel, W , to the hub of which said pulley is united, when turned forward, by means of a friction-clutch, 30 c^3 . The wheel is fastened on the shaft by means of a screw, s^5 . The pulley is driven by a band from a driving-pulley, and by its other groove transmits independent motion by a band to a bobbin-winder or other attachment, 40 when driven backward, without driving the shaft S' . When said pulley is driven forward, as aforesaid, an even motion is imparted to the shaft S' , and therethrough to the needle-bar in the most direct manner, and consequently 45 with the least loss of power. Said shaft S' has a crank, C' , within the arm A , in line with the center of the upright portion or standard of said arm, and the wrist of said crank is embraced by the journal-head of a lever-pitman, 50 L' , the slot of which embraces a rocking fulcrum, F' , which is supported within the standard by an axial screw, as shown in Figs. 4 and 5. The lower end of the pitman L' is connected by a pivot-screw to a short link, L^2 , which, in 55 turn, is connected by a pivot-screw to a crank-disk, D^3 , on the adjacent end of the shaft S^2 , the other end of which carries the shuttle-driver, as aforesaid. This shaft S^2 is supported parallel to the shaft S' by hanger-bearings b^3 60 b^4 , cast on the bottom of the cloth-plate C , and rotates freely therein, but in a direction the reverse of that of said shaft S' , as illustrated by arrows in Figs. 1 and 5, and with an uneven motion, which is the object of said lever-connection.

By inspecting Figs. 1 and 5 it will be seen that in the position of the parts shown in these

and all the other views of the machine, when the shuttle S is ready to release the needle-loop, as shown in Fig. 1, the lower shaft is approaching its point of slowest motion, which is reached when the crank C' is on its upper center, the power end of the lever being then longest and the motion of the other end correspondingly reduced. An important advantage is thus gained in the operation of the shuttle, which, being loose, does not immediately partake of the change of speed, but by its momentum speeds ahead of the shaft-controlled driver, and thus permits the needle-loop to escape freely between. Another advantage of the fast-and-slow motion is the accommodation of a central bobbin of ample size, the shuttle containing such bobbin being carried through the needle-loop at the faster speed of the shaft, and consequently within a relatively short time.

A rotary upper shaft, to receive the even motion of the motor, is essential to said employment of a fast-and-slow under shaft, as will be observed, and by the employment of such upper shaft I am also enabled to employ a positive and independent take-up lever, T , which lets down ample slack for the shuttle, and is adapted to give down and take up thread while the needle is stopping and starting, or, in fact, may receive any required movement. (See Figs. 3 and 4.) Said take-up lever T projects through a slot in one edge of the head H , being pivoted parallel to the shaft S' and behind it, and is operated by a cam-groove, c^4 , of the required shape, which is formed at the back of the disk D' , and is traversed by a stud-pin on the lever. I have shaped and timed the said cams so as to let down thread as soon as the needle enters the goods, and until the greatest diameter of the shuttle is through the needle-loop, and to take up rapidly in conjunction with the feed during the slow motion of the under shaft and the descent of the needle to the cloth.

The spool s is mounted on a spindle, s^6 , on the top of the arm, and the upper thread, 1 , is carried therefrom first through a spring-plate guide, g' , on the back of the head H , behind the arm A ; thence to a rotary disk-tension device, t' , beneath the arm on the back of the head H ; thence to the eye of the take-up lever T , and thence through a guide, g^3 , at the bottom of the head, and a threading-hole, h' , at the bottom of the needle-bar B , directly into the groove and eye of the needle. The take-up is thus adapted to pull directly upward on the thread without drawing it over so many friction-points, as in former machines, while the arrangement of parts is neat and convenient.

To facilitate assembling the parts of the rotary-shaft mechanism within the arm A , as aforesaid, the bearing at the right-hand end of the shaft A' is made a part of a plate, b' , which is attached by means of screws after said parts are in place. Said bearing-plate and the face-plate of the head H being off, the naked crank-

shaft is introduced endwise and pushed through to receive the crank-disk D', which is held in place thereon by the ordinary radial set-screw and an axial wedge-screw, as shown in Fig. 4, 5 with its wrist ninety degrees behind that of the crank C'. (See Figs. 3 and 5.) The shaft is then drawn back into position. The lever-pitman L', introduced endwise through the standard, is attached by means of a screw-driver inserted through an orifice, o, Fig. 5, in the back of the arm, the shaft being turned to bring the screws successively opposite said orifice. The bearing-plate b' is then secured in place and is followed by the pulley P and 15 wheel W.

An improved four-motion feed mechanism is formed, as shown in Figs. 6 and 7, by means of a simple lifting-and-lowering cam, c', combined with the shuttle-driver disk D', as afore-

20 said, a single-acting stroke cam, c⁶, fastened on the shaft S², immediately behind its adjacent bearing, b³, a pair of yokes, y' y², embracing said cams, a lever-link, l', connecting said yokes, a horizontal guide-pin, p', supporting the slotted outer end of said yoke y', a spring, s', arranged within a recess in said yoke y' and pressing against said pin p' to supplement the action of said cam c⁶, and a fulcrum, f', projecting in front of the lever-link l'.

25 To accommodate and support the feed mechanism, the cloth-plate C is provided with a pair of depending lugs, l² l³, at its rear edge, and a longitudinal slot, s⁷, in front of the arm-standard. The former are drilled to receive the pin 30 p' and a parallel slide, s⁸, from which the fulcrum f' projects in the form of a hook. Said slide s⁸ projects from the end of a flat rod, r', which extends diagonally across to the slot s⁷, where it terminates in a nut end, and a thumb-

35 screw, s⁹, passing through said slot, clamps said nut end against a planed boss, through which said slot is formed. The milled head of said screw s⁹ corresponds in position and movement with other stitch-regulators; but with the

40 present mechanism it operates to fasten the fulcrum f' at different points, and thereby to vary the throw of the feed-dog d, which is carried by the yoke y', without changing the duration of the respective feed-motions, the full 45 stroke of the cam c⁶ being used at all times.

The advantage of this peculiarity is uniformity of relation between the feed and take-up under all circumstances and a consequent superior uniformity in the perfection of long and short 50 stitches. The feed mechanism is, moreover, of superior simplicity, compactness, and positiveness.

55 The feed-dog d projects over the shuttle S and works through a suitable opening in a thin plate, which completes the cloth-plate surface at this point, the dog extending on both sides of the needle-hole, as shown in Fig. 4, so as to equalize the strain on the cloth. To regulate the prominence of the feed-dog, its serrated upper part or the dog proper is held between vertical lugs on the top of the yoke y' by a vertical screw, s¹⁰, and a horizontal slotted wedge,

w, is interposed, as clearly shown in Figs. 4 and 7.

The cloth-presser, opposed to the feed-dog, 70 is all that remains to be described. This is specially illustrated by Figs. 1, 2^b, and 3. The presser-bar B² is constructed with a notched and threaded lower end to receive a foot, F, having a lateral shank-slot, s¹¹, and above the 75 same a milled nut, M, by which the foot is securely clamped in position, said slot adapting the shoe to be adjusted with reference to the needle more readily than other forms. The foot may be otherwise of any preferred make, but 80 is preferably stamped out of soft plate steel and hardened in the form shown. The lifter L is of a common form, attached by a pivot-screw to the face of the head H; and P² represents an axial screw adjusting a coiled presser-spring 85 within the head in a common way.

The above description will enable those skilled in the art to make and use my said machine and its several parts.

Details which are not particularly described 90 are clearly shown in the drawings or may be of a well-known description.

I do not herein claim the combination, in a sewing-machine, of a rotary shuttle having an open bobbin-chamber in its outer face and a circumferential guide flange or projection, a circular shuttle-race grooved to receive said flange, a cap-plate attached by screws and having a concentric opening to expose said bobbin-chamber, a bobbin removable at will through said 100 opening, and a combined feed-cam and shuttle-driver located parallel to said shuttle-race, and having a projection extending into the latter behind the heel of said shuttle; nor the combination, in a sewing-machine, of a rotary 105 shuttle having an open bobbin-chamber in its outer face and a circumferential guide flange or projection, a circular shuttle-race grooved to receive said flange, a cap-plate attached by 110 screws and having a concentric opening to expose said bobbin-chamber, a bobbin removable at will through said opening, and a combined feed-cam and shuttle-driver located parallel to 115 said shuttle-race, and having a projection extending into the latter behind the heel of said 120 shuttle, said projection being constructed with a deep peripheral notch or groove forming a detached horn at the rear end of said projection, these features being claimed by me in an application for patent filed December 31, 1877. 125

What I now claim as new, and desire to protect by Letters Patent of the United States, is—

1. A rotary shuttle having an open bobbin-chamber in its outer face and provided with 125 an attached latch and ejector for releasing and throwing out the bobbin without disturbing the shuttle, in combination with a shuttle-race having an annular cap, the opening of which exposes said bobbin-chamber and latch, substantially as herein described.

2. A rotary shuttle having an open bobbin-chamber in its outer face and a recessed hub within said chamber, and provided with a fin.

ger-lever projecting through an opening in said face and a sliding latch projecting through said hub, as herein specified.

3. A rotary shuttle having an open bobbin-chamber in its outer face and provided with a finger-lever projecting through an opening in said face and terminating in an ejector-finger at the back of said chamber, as herein specified.

10 4. A rotary shuttle having an open bobbin-chamber in its outer face, a central hub within said chamber and a central latch, and provided with an annular bobbin-case, an annular bobbin within said bobbin-case, and an adjustable tension device on the exposed annular face of said bobbin-case, as herein specified.

5. A segmental rotary shuttle constructed with an axial bobbin-chamber and a peripheral guide-flange, and having its wider intermediate portion made light, substantially as herein described, in combination with a concentric shuttle-race and its cap and a rotary shaft carrying a shuttle-driver which projects behind the heel of said shuttle, as specified.

25 6. The combination of the rotary shuttle-driver D with its fastening-screw s⁴, and the shuttle-driver disk D², having a concentric series of screw-holes, h⁴, for adjusting said driver, substantially as herein specified.

30 7. The combination, in a sewing-machine, substantially as herein described, of a circular shuttle-race, a segmental disk-shuttle rotating freely within said race, an under shaft carrying a rotary-shuttle driver which nearly fills the space within said race behind the heel of the shuttle, an upper shaft provided with the driving-pulley, and mechanism for transmitting an alternately fast and slow motion to said under shaft from said upper shaft, the 35 moving parts being arranged and timed, as specified, for periodically opening a limited space behind the heel of the shuttle to release the needle-loops, in the manner set forth.

8. The combination, in a sewing-machine, 45 substantially as herein described, of a circular shuttle-race, a segmental disk-shuttle having a central bobbin and rotating freely within said race, an under shaft carrying a rotary-shuttle driver which nearly fills the space 50 within said race behind the heel of the shuttle, an upper shaft provided with the driving-pulley and with a needle-driver, mechanism for transmitting an alternately fast and slow mo-

tion to said under shaft from said upper shaft, and a reciprocating needle-bar carrying the 55 needle, the moving parts being arranged and timed, as specified, for the purposes set forth.

9. The combination, in a sewing-machine, substantially as herein described, of a circular shuttle-race, a segmental disk-shuttle having 60 a central bobbin and rotating freely within said race, an under shaft carrying a rotary-shuttle driver, which nearly fills the space within said race behind the heel of the shuttle, an upper shaft provided with the driving-pulley and with a needle-driver and take-up-cam mechanism for transmitting an alternately fast 65 and slow motion to said under shaft from said upper shaft, a reciprocating needle-bar carrying the needle, and a take-up lever actuated by 70 said cam, the several parts being arranged and timed, as specified, for the purposes set forth.

10. The combination, with the head H and the take-up lever T, projecting at one edge of said head, of mechanism within said head for 75 operating said lever and the thread-guides g³, and tension device t', attached to the back of said head, and threaded, as herein specified, said tension device being arranged immediately above the lower thread-guide, and said 80 take-up lever taking its bight of thread from between said tension device and lower thread-guide, as shown, for the purposes set forth.

11. The combination, with the hollow arm A and a crank-shaft within the horizontal portion of said arm, of the bearing-plate b', forming 85 a part of the standard and constituting one of the bearings of said shaft, and screws attaching said bearing-plate, as herein specified, for the purpose set forth.

12. In combination, the cloth-plate C, having a longitudinal slot, s⁷, in front of the standard, and parallel depending lugs l² l³ behind the feed-slot, the thumb-screw s⁹, diagonal rod r', slide s⁸, fulcrum f', lever-link l', yokes y¹ y², 95 and cam c⁶, as herein specified, for the purpose set forth.

13. In combination, the adjustable feed-dog d, the slotted horizontal wedge w, the vertical screw s¹⁰, and the yoke y', adapted to receive 100 and carry said feed-dog and adjusting devices, substantially as herein specified.
